CLAIM

The ornamental design for a multiple speaker control switch with a liquid crystal display for a vehicular radio receiver and cassette player, as shown and described.

DESCRIPTION

FIG. 1 is a perspective view of a multiple speaker control switch with a liquid crystal display for a vehicular radio receiver and cassette player. The broken line showing is included for the purpose of illustrating environmental elements only and forms no part of the claimed design;

FIG. 2 is a front elevational view of a multiple speaker control switch for a vehicular radio receiver and cassette player showing my new design on an enlarged scale;

FIG. 3 is a rear elevational view thereof;

FIG. 4 is a side elevational view thereof as viewed from a point beneath the showing of FIG. 2, the remaining side elevational views of the multiple speaker control switch being identical therewith;

FIG. 5 is a cross-sectional view along line 5—5 of FIG. 2;

FIG. 6 is a cross-sectional view along line 6—6 of FIG. 2;

and,

FIG. 7 is a front elevational view of the multiple speaker switch displaying the liquid crystal display depicting gradations of sound.
